UNITED STATES PATENT OFFICE.

FRED ERNEST WHITE, OF GARDNER, MASSACHUSETTS, ASSIGNOR TO THE CENTRAL OIL & GAS STOVE COMPANY, OF GARDNER, MASSACHUSETTS, A CORPORATION OF MASSACHUSETTS.

HEAT DEFLECTOR.

Application filed January 17, 1922. Serial No. 529,959.

To all whom it may concern:

Be it known that I, FRED E. WHITE, a citizen of the United States, and resident of Gardner, in the county of Worcester and 5 State of Massachusetts, have invented certain new and useful Improvements in Heat Deflectors, of which the following is a specification.

This invention relates to ovens of the 10 type used for cooking purposes and more particularly to such ovens having the heated air entering at the bottom thereof.

The principal object of my invention is to provide deflecting means for said heated air 15 at the entrance to the oven, whereby a complete circulation takes place within the oven and an even temperature obtains in all parts thereof.

Another object of this invention is to 20 provide a deflector of the type described with proper construction and of sufficient body so as to arrest and properly distribute the heat throughout the oven, thereby restricting the direct upward radiation from 25 the burner. In case of previous distributors, it has been found that unless sufficient insulation is provided in this member, heat passes too readily to the bottom of the cooking utensils.

30 Still another object of my invention is to provide a device of such a shape that it will be well braced throughout to prevent warping due to continued heating, and which may be readily inserted or removed from an oven 35 of the above type.

With these and other objects in view my invention consists in a device having a dead air space between the entrance of the heated air to the upper portion of the oven, of 40 such a shape that the heated air striking the lower surface of the deflector will circulate freely to all parts of the oven, said device having attached means for readily supporting it within the oven.

45 These and other objects I secure by the use of the construction, arrangement, and combination of parts more fully hereinafter described; and with reference to the accompanying drawings, in which—

50 Figure 1 is a perspective of a preferred form of device;

Fig. 2 is a transverse sectional view;

Fig. 3 is a view of an oven showing this device in use.

55 Referring now more particularly to these

drawings, which are merely illustrative of a satisfactory form of device and to which I do not wish to be limited, as various changes and modifications will occur to those skilled in this art, the device is shown to consist of 60 a body portion 1 being substantially V-shape, having end pieces 2 secured thereto and a top portion 3 enclosing the edges of the body portion 1 and the lapped ends of the end pieces 2. A lining of asbestos 4 may be 65 arranged within the device to more fully insulate the air space enclosed within the parts. Perforations 5 may be provided in the device where the joints between the ends, body and top are of such a nature that upon 70 heating the trapped air within the container would expand with disruptive force. Hook shaped parts 6 may be provided, shown integral with the top portion 3 for convenience of manufacture, which are adapted to 75 engage the supporting racks or like members designed to receive the removable shelves on the oven.

It will now be seen that the dead air space in connection with the lining of asbestos will entirely insulate the top portion, and the sloping faces of the bottom portion will deflect the heat in a continuous circulation throughout the oven, giving an even distribution of temperature with the obvious 80 beneficial results.

If desired, the entire device may be enamelled, oxidized, or treated in any suitable manner to prevent rust, or to give an attractive appearance to the whole.

What I claim is:

1. In combination, an oven chamber having a heated air entrance, a deflector for said heated air in proximity to said entrance, including an enclosed dead air space whereby the heated air is deflected and freely circulated by said deflector into said oven chamber.

2. The device of claim 1, said dead air space comprising a body substantially triangular in transverse cross section, said body being lined with an insulating covering.

3. The device of claim 1, with a hook-shaped member at each end thereof, said device being adapted to be removably supported in the oven by said hook-shaped member.

In testimony whereof, I affix my signature.

FRED ERNEST WHITE.
